(57) **CLAIM**

The ornamental design for a off-road vehicle, as shown and described.

DESCRIPTION

FIG. 1 is a front and left-side perspective view of the off-road vehicle showing my new design:

FIG. 2 is a rear and right perspective view thereof;

FIG. 3 is a left-side elevation view of the utility vehicle, wherein the opposing right-side is a mirror image thereof;

FIG. 4 is a top plan view thereof;

FIG. 5 is a front elevation view thereof;

FIG. 6 is a rear elevation view thereof; and,

FIG. 7 is a front and left-side perspective view thereof with the front cover panel removed.

The broken line showing parts of the structural frame, seat, wheels, tires and other mechanical components are for the purpose of illustrating portions of the off-road vehicle and form no part of the claimed design.

Furthermore, the stipple shading shown on the thickened sleeves over some of the tubular frames are provided for the purpose of illustrating a contrast in material. No specific materials, however, are claimed.

1 Claim, 7 Drawing Sheets
